UNITED STATES PATENT OFFICE.

JOHN WILLIAM WAITZ, OF OIL CITY, PENNSYLVANIA; JUDSON D. TRAX AND WILLIAM M. PARKER EXECUTORS OF SAID WAITZ, DECEASED.

PROCESS OF PRODUCING GASOLENE.

1,105,727.

Specification of Letters Patent.

Patented Aug. 4, 1914.

Application filed July 6, 1912. Serial No. 708,058.

To all whom it may concern:

Be it known that I, JOHN W. WAITZ, citizen of the United States, residing at Oil City, in the county of Venango and State of

5 Pennsylvania, have invented certain new and useful Improvements in Processes of Producing Gasolene, of which the following is a specification.

The object of this invention is, to provide 10 a process whereby the lighter hydrocarbon liquids and vapor—particularly gasoline—may be extracted from the earth's strata wherein they are contained, and more especially in the older developed territories, 15 where the natural gas pressure has become reduced to such an extent that it will not flow spontaneously from wells which have been drilled into the producing strata, or where the supply of such hydrocarbons has 20 supposedly been well-nigh exhausted, or does not exist in sufficiently large quantities to pay for operating the wells by any of the methods now employed.

My improved process of producing gasolene consists essentially in passing air or gas 25 or a mixture of the same, under pressure, (that is, compressed air or gas,) of comparatively low temperature, through a stratum in which hydrocarbon fluids are contained, 30 during which passage said air or gas, by reason of a rise in temperature, absorbs a certain amount of hydrocarbon vapor and becomes saturated therewith, then reclaiming or recovering said saturated air or gas 35 and causing the same to pass through a condenser wherein said vapor is caused to condense and precipitate, then withdrawing said condensation from said condenser, as the product of this process.

40 The drawing is a more or less ideal illustration showing a vertical section through a portion of the earth, pierced by two wells through which my process is carried out; the equipment in said wells being shown partly 45 in vertical section and partly in elevation. It should be understood, however, that said drawing is illustrative merely, and does not purport to shew the only way in which my process may be reduced to practice; for instance, what is herein termed a "point of relief" is shown as an oil-producing well,—it need not necessarily be such, neither need the point of injection be a well,—it may be 50 any other means whereby the pressure-fluid may be injected into the producing strata or

brought into contact with the hydro-carbon fluid or producing stratum within a well, and said fluid pressure may thereafter be withdrawn from the same well.

As shown in said drawing, I utilize a well 60 1, which has been drilled as a gas or oil well and is provided with a casing 2, equipped with a casing-head 3, of substantially the usual type employed in the equipment of such wells. Into said well is inserted a pipe 65 4, through which air or gas under pressure is conducted to the oil or gas-producing stratum 5. Preferably, the lower end of said pipe rests upon the bottom of the well and is perforated as at 6, to cause the escape 70 of the pressure-fluid, in proximity or at the producing stratum. Above said producing stratum, a wall-packer is located in the well, for the purpose of confining the pressure within the well, so that it must all pass 75 into said producing stratum. A well equipped as above described, I term a "pressure well", and this pressure well is located in a position which is substantially central to a group of producing wells which are to 80 be connected for the application of my process. To the casing-head 3' of one or more wells, as 7, through which said pressure-fluid is to be recovered, I attach the suction or intake-pipe 8 of an air or gas-compressor 85 9. The discharge-pipe 10 of said compressor is connected to a condenser, which consists substantially of a closed shell or cylinder 11, adapted to contain a refrigerating fluid 12, such as brine, and in which is inclosed or 90 contained a condensation-chamber 13, through which the recovered vapor is caused to pass. From the bottom of chamber 13, a pipe 14 leads to the outside of the condenser, and is adapted for the withdrawal of 95 the condensed fluid into any suitable receptacle, such as barrel 15. From the condensing-chamber, a suitable pipe 16 or conduit is passed to the pressure well and said pipe may be equipped with the necessary valve, 100 as 17, to control or regulate the admission of the pressure fluid into said pressure well.

The precise form of equipment of the producing well is not material, the only essential being that it should be cased in the usual 105 way with a casing, such as 2', and provided with a casing-head 3', which may also be of the usual form, and to which the intake-pipe of the compressor may be connected for the recovery of the pressure fluid, as above 110

stated. If the well passes through a water-bearing stratum, a well-packer should, of course, be employed in the usual way and for the usual purpose. The producing well 5 may be what is termed a gas well, having a product of gas only, or it may be, or have been, an oil well. As shown in the drawing, however, said well is equipped as an oil well, the equipment being my deep well fluid-dis- 10 placing device, shown and described in a certain application for Letters Patent of the United States, filed by me on the 15th day of May, 1911, Serial No. 627,185.

Summary: As will be readily understood 15 from the foregoing specification, together with an inspection of the drawings, the process herein set forth is essentially as follows: Either a suitable gas, such as natural gas, or air, or a mixture of both, is compressed to a suitable pressure; it is then refrigerated or cooled, preferably to a temperature below that of the oil or gas-producing stratum of the earth, which temperature varies somewhat according to depth, and 20 slightly as to locality, but in this part of the Pennsylvania field, at the depth of 1000 feet, said temperature is approximately 70° F. The air, after being cooled, as stated, is then injected into and caused to permeate and 25 pass through a certain area of such stratum to a point of relief, as indicated by the arrows in the drawing; and in said passage, the rise of temperature which takes place, together with the affinity of the pressure 30 fluid for hydro-carbon vapor, causes it to become saturated with said vapor; said vapor is then recovered at said point of relief and again refrigerated, thus causing a 35

precipitation of the vapor therein, which vapor is suitably confined and withdrawn 40 as the product of this process.

I claim:

1. The herein described process of producing gasolene, which consists in compressing a suitable fluid, then refrigerating the 45 same, then passing said fluid through a stratum of the earth containing hydro-carbon vapor, then recovering said fluid, then causing a precipitation of the vapor therefrom.

2. The herein described process of producing gasolene, which consists in compressing a suitable gas, then cooling the same, then injecting said gas into a stratum of the earth which contains hydro-carbon fluids 55 and wherein said gas becomes saturated with vapor from such fluids, because of a rise in temperature, then recovering said gas at a suitable point of relief, then causing said vapor to condense.

3. The herein described process of producing gasolene which consists in compressing a suitable gas, then cooling the same, then causing said gas to pass into absorptive relation with a hydro-carbon fluid within a 65 well which produces such fluid, whereby said gas becomes saturated with vapors from such fluid due to a rise of temperature then recovering said gas from said well and causing a precipitation of the vapors therein.

In testimony whereof I affix my signature in presence of two witnesses.

JOHN WILLIAM WAITZ.
